UNITED STATES PATENT OFFICE.

GEORGE KOMARCSEVITS AND FRANK G. NUNN, OF CLEVELAND, OHIO.

SAFETY DEVICE FOR LOCKS.

Application filed January 13, 1925. Serial No. 2,101.

To all whom it may concern:

Be it known that we, GEORGE KOMARCSEVITS and FRANK G. NUNN, citizens of the United States of America, residing at Cleveland, in the county of Cuyahoga and State of Ohio, have invented certain new and useful Improvements in Safety Devices for Locks, of which the following is a specification.

10 This invention relates to certain new and useful improvements in safety devices for locks and has for its primary object to provide a safety device adapted to be removably positioned within a key hole opening 15 of a door lock to prevent the positioning of the key in the opening for attempted unauthorized operation of the lock structure.

A further object of the invention is to 20 provide a safety device for locks that embodies an obstruction positionable in a key opening slot of the type operable from the inner and outer sides of the door and wherein the lock tumblers are out of alignment 25 with the key hole slot with a special type of positioning key for placing the safety device in position against unauthorized removal and also for removing the same when it is desired to operate the lock mechanism.

30 With the above and other objects in view that will become apparent as the nature of the invention is better understood, the same consists of the novel form, combination and arrangement of parts hereinafter more fully 35 described, shown in the accompanying drawings and claimed.

In the drawings, wherein like reference characters designate corresponding parts throughout the several views,

40 Figure 1 is a vertical longitudinal sectional view through a portion of a door and casing with a portion of the lock casing broken away with the safety device positioned in the key hole slot,

45 Figure 2 is an edge elevational view of the door, partly broken away and shown in section with the side and positioning key in the lock structure with the key ready for removal and disengagement from the safety device,

50 Figure 3 is a horizontal sectional view taken on line III-III of Fig. 2,

Figure 4 is a horizontal sectional view, similar to Fig. 3 showing the safety device 55 partially removed from the lock,

Figure 5 is a side elevational view of the safety device with the positioning key disengaged therefrom,

Figure 6 is a side elevational view, similar to Fig. 5, partly broken away and shown 60 in section with a portion of the positioning key operatively engaging the safety device,

Figure 7 is an edge elevational view of the safety device,

Figure 8 is a vertical cross-sectional view 65 taken on line VIII-VIII of Fig. 5, and

Figure 9 fragmentarily illustrates side and end elevations of the positioning key.

Referring more in detail to the accompanying drawings and particularly to Fig. 70 1, there is illustrated a door 1 having a lock casing 2 embedded in one edge thereof, the door moving into engagement with the frame 3 and so retained by the latch 4. The lock casing 2 is of the type that has the 75 comparatively large unobstructed key receiving slot 5 with the tumbler mechanism 6 of the lock spaced upwardly of the slot 5 as shown in Figs. 1 and 2.

The principal object of the invention is 80 to place an obstruction or safety device in the key receiving slot 5 to prevent the entrance of a key in the slot for unauthorized operation of the lock mechanism and the safety device embodies a cylindrical 85 shank 7 that carries a lateral ward 8 spaced from the ends of the shank as shown in Figs. 5 and 6. A plate 9, preferably formed of sheet metal that is folded upon itself to form a cylindrical barrel 10 is rotatably 90 supported on the other end of the shank 7, fingers 11 carried by one of the plate sections as shown in Figs. 5 and 7 being bent over the other plate section to retain the same in position.

To retain the plate 9 upon the shank 7, the latter is provided with an annular shoulder 12 that is engaged by the adjacent edge of the barrel portion 10 of the plate and said barrel portion has one side thereof 100 cut away or provided with an opening 13 into which the pin 14 carried by the shank 7 extends as clearly shown in Figs. 5 and 8, the pin 14 engaging the adjacent side wall of the opening 13 to retain the outer 105 edge of the barrel portion in engagement with the shoulder 12.

The plate 9 is resiliently maintained in adjusted position by the spring finger 15 carried by the lower edge wall of the open- 110

ing 13 and selectively engaging either of the flat faces 16 upon the shank 7 as shown in Figs. 5 and 6.

The outer end of the shank 7 within the barrel portion 10 of the plate is reduced as at 17 and has an outwardly directed pin carried thereby adjacent its inner end. The positioning key 19 includes a tubular shank having a bayonet slot 20 in its outer end, the outer end of the key shank being received on the reduced end 17 of the shank 7 for positioning the pin 18 in the bayonet slot 20.

With the ward 8 and plate 9 disposed in alinement as illustrated in Figs. 5 and 6, the positioning key is engaged with the reduced end 17 of the shank 7 of the safety device and the latter is positioned in the key slot 5 as shown in Fig. 4, the ward 8 being located in the lock casing 2 while the plate 9 lies in the key slot 5 at one side of the door. Upon rotating the positioning key, the shank 7 is rotated to dispose the ward 8 in a horizontal plane while the plate 9 remains vertically positioned in the key slot 5. The safety device is then completely moved into the lock casing and the forward end of the shank 7 is received in the opposite key slot as shown in Figs. 3 and 4 to 25 provide a bearing and support for the safety device, and upon a further rotation of the positioning key 19 the ward 8 is vertically positioned while the plate 9 is horizontally disposed as shown in Figs. 1 to 3. 30 A partial reverse rotation of the position key 19 will disengage the pin 18 from the bayonet slot 20 of the key and permit withdrawal of the latter. With the safety device supported in the key opening of the lock structure the insertion of a skeleton key or the like for purposes of operating the lock mechanism will be prevented. In removing the safety device from the lock, the key 19 is engaged with the reduced end 45 17 to position the plate 9 in alinement with the adjacent key slot 5 to shift the safety device with the plate 9 into the adjacent key slot 5 and upon a reverse rotation of the shank 7 the ward 8 will be alined with the key slot to permit ready removal of the safety device. If desired, the ward 8 may be constructed in a manner for cooperation with the tumbler mechanism 6 of the lock structure and when positioned as illustrated 50 55 in Fig. 4 may effect operation of the lock structure to release the bolt 4.

While there is herein shown and described the preferred embodiment of the

present invention, it is nevertheless to be understood that minor changes may be made therein without departing from the spirit and scope of the invention as claimed.

What is claimed as new is:—

1. A safety device for locks comprising in combination with a lock having opposite unobstructed key receiving slots there-through, a safety device embodying a shank having one end supported in a slot at one side of the lock, a ward carried by the shank, a plate rotatably supported on the shank and projecting laterally therefrom, a pin projecting from the shank adjacent the plate, a positioning key for the safety device having a tubular shank and bayonet slot in its side wall to receive the pin and rotate the shank to position the plate in a horizontal plane and the ward vertically, and means for retaining the plate in position on the shank including an annular shoulder on the shank, a portion of the plate bearing being cut away with one edge of the plate bearing engaging the shoulder and a pin carried by the shank within the cut away portion and engaging one side thereof to hold the plate bearing in engagement with the annular shoulder.

2. A safety device for locks comprising in combination with a lock having opposite unobstructed key receiving slots there-through, a safety device embodying a shank having one end supported in a slot at one side of the lock, a ward carried by the shank, a plate rotatably supported on the shank and projecting laterally therefrom, a pin projecting from the shank adjacent the plate, a positioning key for the safety device having a tubular shank and bayonet slot in its side wall to receive the pin and rotate the shank to position the plate in a horizontal plane and the ward vertically, the end of the shank inclosed by the plate being reduced, said pin being housed by the bearing portion of the plate, and means for retaining the plate in position on the shank including an annular shoulder on the shank, a portion of the plate bearing being cut away with one edge of the plate bearing engaging the shoulder and a pin carried by the shank within the cut away portion and engaging one side thereof to hold the plate bearing in engagement with the annular shoulder.

In testimony whereof we affix our signatures.

GEORGE KOMARCSEVITS.
FRANK G. NUNN.
